UNITED STATES PATENT OFFICE.

CONSTANCE MARY GIDLEY, OF COLLUMPTON, ENGLAND.

FASTENER FOR CUFFS.

SPECIFICATION forming part of Letters Patent No. 634,167, dated October 3, 1899.

Application filed October 14, 1898. Serial No. 693,493. (No model.)

To all whom it may concern:

Be it known that I, CONSTANCE MARY GIDLEY, of Collumpton, county of Devon, England, have invented a certain new and useful 5 Improvement in Fasteners for Cuffs, of which the following is a specification.

The object of my improvement is to provide a simple, cheap, and efficient fastener for cuffs, such as are worn by women with long-sleeved dresses, and it is specially intended 10 for what are commonly called "turn-over" cuffs, or, in other words, cuffs which are folded midway between the ends, so as to form an inner portion surrounding the wrist and an outer 15 portion lapping over the sleeve of the dress.

My improvement consists in a wristlet or bracelet for embracing the wrist or wrist portion of the dress-sleeve and provided with a projection or number of projections for directly or indirectly engaging the cuff—as, for 20 example, through an ordinary buttonhole or studhole formed in a cuff.

In the drawings, Figure 1 is a perspective view of a simple form of wristlet embodying 25 my improvement. Fig. 2 is a sectional view showing it engaged with a cuff and applied to the wrist portion of a dress-sleeve.

Similar letters of reference denote corresponding parts in both figures. 30 A designates a wristlet or bracelet, here shown as consisting of a piece of flexible material. Preferably it will be made of resilient material, and probably the most advantageous material for its construction will be resilient 35 metal of some kind. I have shown this piece of material as made transversely flat and quite thin. It will be seen by this construction it will be well adapted to engage with the material of a dress-sleeve, so as to prevent it 40 from slipping out of place. If intended to apply directly to the wrist, of course it will be made of a shape more comfortable to the

wearer. In either case it will be generally ellipsoidal, and preferably its ends will be overlapped, as they will be then less likely to 45 become indented in the sleeve in such a way as to hurt the wearer. Obviously the ends may be sprung apart sufficiently to facilitate the placing and removing of the wristlet or bracelet. 50

B designates a projection made in the form of the head of a stud. It is fastened to the middle portion of the wristlet or bracelet and is adapted to engage directly with a suitable buttonhole formed in the cuff. Obviously 55 there may be a greater number of projections, and if it were desired to give more play to the cuff than would result from the direct engagement of a stud-like projection with the buttonhole an intermediate link or pivotal section 60 might be employed.

By my improvement I produce a simple, cheap, and efficient means for fastening cuffs in place, and thus obviate the necessity for the expedients heretofore employed, such as 65 ordinary pins, safety-pins, and pieces fastened to the dress-sleeve.

What I claim as my invention, and desire to secure by Letters Patent, is—

A wristlet or bracelet composed of a strip 70 of thin spring material suitably shaped to embrace and embed itself in the material of the wrist portion of a sleeve, and made with resilience tending to contract, and provided with a projection or projections for engaging 75 a cuff.

In testimony whereof I have signed my name to this specification in the presence of two subscribing witnesses.

CONSTANCE MARY GIDLEY.
